UNITED STATES PATENT OFFICE.

FRANK H. PLAISTRIDGE, OF LOS ANGELES, CALIFORNIA.

FLY-PAPER BRACKET.

SPECIFICATION forming part of Letters Patent No. 680,463, dated August 13, 1901.

Application filed March 5, 1901. Serial No. 49,957. (No model.)

To all whom it may concern:

Be it known that I, FRANK H. PLAISTRIDGE, a citizen of the United States, residing at Los Angeles, in the county of Los Angeles and State of California, have invented a new and useful Bracket to Support Fly-Paper, of which the following is a specification.

The objects of my invention are to provide a handy, cheap, and reliable means to support fly-paper and to keep the paper upon which the flies become entangled out of the way and the flies sticking thereto out of view. I accomplish these objects by means of the device described herein and shown in the accompanying drawing, which is a perspective view of my fly-paper-holding bracket in condition to receive the sticky fly-paper.

Referring to the drawing, B represents resilient wires, each of which is passed through openings in three or more longitudinal slats A and holds the slats in place to form a platform upon which the fly-paper is placed. These wires are bent over upon themselves so that the upper and projecting end of each wire bears against the middle of the strip and is adapted to securely hold anything that may be placed on the longitudinal strips under the projecting ends of the wires. In the back strip and projecting rearwardly from a central point therein is a wire loop for hooking the bracket to a nail or screw in the side of the wall. This wire supporting-loop has an offset portion C', which is bent at right angles to the plane of the face of the longitudinal strips, the purpose being to support the face of the bracket-platform in a horizontal position when the upper portion of the supporting-loop is hooked onto a nail or screw, the points C' on the wire where the wire bends to form an offset being adapted to rest against the face of the wall or upright support and hold the platform of the bracket in a horizontal position.

A convenient place anywhere on the wall where it is desired to hang one of my brackets is selected and the upper part of the supporting-loop is passed over a nail-head or screw in the face of the wall or support. This should be at an elevation from the floor, so as to be out of the way of any one passing under it. When in proper position against the wall, a sheet of sticky fly-paper is passed over the

face of the platform and under the projecting ends B' of the wire and is securely held thereby on the platform, so that it cannot be accidentally removed. Now this paper will be out of sight, an objection to the use of fly-paper being thus removed. When flies become entangled on the fly-paper, they are very offensive to the sight of many persons; but by the use of my bracket a convenient place is always ready to receive the paper. It is always out of the way, and whatever may be entangled thereon is never seen by those in the room, not even by those within a few feet of the bracket.

This simple bracket affords ready means to instantly remove an old or used paper and replace the same with a new one.

Having described my invention, what I claim as new, and desire to secure by Letters Patent, is—

1. A fly-paper-holding bracket, comprising a horizontal platform to hold the paper; springs to removably secure the paper thereon; and means to support the same on the wall.

2. A fly-paper-holding bracket, comprising the longitudinal platform-strips A; transverse connecting-wires B, to secure said strips to said wires, being bent at their rear ends upwardly and forwardly, the projecting end bearing against the central strip and the supporting-wire C, secured to the rear strip and bent upwardly at right angles to the platform, substantially as shown and described.

3. The herein-described bracket for holding sticky fly-paper, comprising a plurality of longitudinal strips forming the bracket-platform; resilient wires to connect these strips extending through the strips and being bent forward and downward, the projecting ends resting against the central strip and adapted to hold the paper on the platform; and a wire loop projecting from the rear strip and bent at right angles to hold the platform level, as shown and described.

In witness that I claim the foregoing I have hereunto subscribed my name this 26th day of February, 1901.

F. H. PLAISTRIDGE.
